LUGGAGE CASE

Allan J. Alvaney, Chicago, Ill., assignor to Sears, Roebuck and Co., Chicago, Ill., a corporation of New York

Application October 12, 1956, Serial No. 43,337

Term of patent 14 years

(Cl. D87—5)

The drawing is a perspective view of a luggage case embodying my new design.

The face of the bottom tray (not seen) is similar to the face of top tray seen in the drawing, except for lack of the circular ornament.

I claim:

The ornamental design for a luggage case, as shown and described.
